UNITED STATES PATENT OFFICE.

WILLIAM HAIG RAMAGE, OF GIRARD, OHIO, ASSIGNOR TO VALLEY MOULD AND IRON CORPORATION, OF SHARPSVILLE, PENNSYLVANIA, A CORPORATION OF NEW YORK.

APPARATUS FOR CASTING INGOT MOLDS AND THE LIKE.

Application filed May 13, 1926. Serial No. 108,816.

This invention relates broadly to metallurgy and more especially to improvements in apparatus for casting ingot molds and the like.

5 The present invention comprises an improvement upon the construction disclosed in the patent to John E. Perry, No. 1,581,541, granted April 20, 1926.

In the present invention, the set-up is 10 similar to that disclosed in the said Perry patent with the exception that the stripping plate is constructed to present a very narrow edge to the matrix wall and is arranged and constructed so that expansion of the 15 inner edge of the plate does not cause warping. Furthermore, the bottom of the matrix comprises a sand surface which leads up to the sand wall on the core bar. In this new set-up substantially no chilling occurs on the 20 bottom of the casting because a substantially continuous sand surface forms the matrix wall.

The stripping plate in the present invention preferably is provided with a tapered 25 inner edge portion so that a cross section thereof is wedge-shaped. In order to avoid wrinkling or warping when the inner edge is heated, the stripping plate preferably is provided with narrow slits or slots extending 30 inwardly preferably at right angles to the edge of the plate, thereby dividing the thin exposed edge of the stripping plate into a plurality of sections, each of which is capable of a slight linear expansion without 35 warping the metal in the plate when the set-up is filled with molten metal. The slots are preferably of such narrow width as will prevent a flow of hot molten metal 40 into these slots in case the same is not filled with sand when the flask rammed.

It is realized that the present invention 45 may be carried out in constructions other than those specifically disclosed and therefore the disclosure is to be understood as illustrative and not in the limiting sense.

Throughout the several figures of the drawings like characters are used to represent like parts.

Figure 1 is a plan view of a pair of stripping plates in accordance with the present 50 invention shown detached from the flask to which the plates are adapted to be secured.

Figure 2 is a perspective detail view of 55 one portion of one of the plates.

Figure 3 illustrates a vertical section

through the set-up of a stool, core bar, stripping plates and flask in accordance with the present invention.

Referring now more particularly to the drawings, the flask 1 is preferably formed of sections which may be secured together by means well known in the art. This flask carries secured to the bottom flange 2, stripping plate sections 4 and 5 which are adapted to be removably, at the same time, securely, attached to the flask so that the stripping plates need only be removed in case of change or repair. These stripping plates are adapted to support a sand wall 6 in the flask and to form guides for centering the flask over the mold pattern when the flask is being rammed. The stripping plates comprise flat portions 7 and beveled inner edges 8. The edges are slotted at 9 at convenient distances, with the slots sufficiently close together to permit the inner edge of the plates to expand when heated, without causing the plates to warp. The slots are sufficiently long to lead back to that portion of the plates which is not subjected to the intense heat of the molten metal. The set-up also comprises a stool 10 in which is mounted a core bar 11 having a sand rammed surface and with the base 12 of the core bar provided with a circular pan 13 adapted to carry a ring 14 of mold sand which forms the bottom wall of the matrix of the set-up. The edges 15 of the base 12 extend beneath the stripping plates 4 and 5 so that the weight of the flask acting on the edges 15 securely positions the core bar in the center of the flask. Suitable key bolts 16 may be provided to position the flask on the stool and to hold the parts in position during pouring operations.

From the foregoing, it will be observed that substantially the entire matrix wall of the set-up is a sand face and with only a very narrow edge of the stripping plate being exposed to the hot molten metal. This narrow edge quickly thickens to a plate of such size as to rapidly carry away such heat as is transmitted to the edge and the slots in the edge prevent warping of the stripping plate.

Having thus described my invention, what I claim is:

1. As an article of manufacture, a stripping plate for use in casting and having the inner edge of said plate comprising individ-

105

110

ualized portions adapted to expand without warping when heated.

2. As an article of manufacture, a stripping plate for use in casting and having the inner edge of said plate slotted to form individualized portions adapted to expand without warping when heated.

3. An article of manufacture comprising a stripping plate for use in casting ingot molds, the inner edge of said stripping plate being provided with openings adapted to permit said edge to expand and contract under influence of heat and cold without warping said plate.

15 4. An article of manufacture comprising a metal stripping plate for use in casting ingot molds, the inner edge of said stripping plate being slotted to permit said edge to expand and contract under influence of heat and cold without warping said plate, and with the inner edge of said plate being thinner than the outer portion of said plate.

25 5. As an article of manufacture, a stripping plate for use in casting, said stripping plate being adapted to be attached to a flask and support the bottom of a sand wall in said flask, the sand supporting portion of said plate being inclined, and provided with slots to permit expansion of the said supporting edge without warping said plate.

30 6. As an article of manufacture, a strip-

ping plate for use in casting, said stripping plate being adapted to be attached to a flask and support the bottom of a sand wall in said flask, the sand supporting portion of said plate being inclined inwardly, and provided with slots leading into the body of said plate remote from intense heat when the device is in use to permit expansion of the sand supporting edge without warping said plate.

35 7. A set-up for casting ingot molds comprising a flask carrying a wall of sand, a core bar, a stool for supporting said core bar, and a stripping plate on the bottom of said flask and adapted to support the lower portion of a sand wall within said flask, the sand supporting portion of said stripping plate being beveled inwardly, said supporting portion of said strip being constructed to expand without warping when heated.

40 8. A set-up for casting ingot molds comprising in combination a flask provided with a sand wall facing, a stripping plate adapted to support the bottom portion of said facing and to expose a thin metal edge beneath said face, a sand covered core bar, and a sand supporting member adapted to support a layer of sand between said metal edge and said core bar to comprise the bottom of the matrix of the set-up.

45 55 60 65 WILLIAM HAIG RAMAGE.
